Primary Examiner — Lilyana Bekic*Assistant Examiner* — Lee D. Starr(74) *Attorney, Agent, or Firm* — JCIP; Joseph G. Chu; Jeremy I. Maynard(57) **CLAIM**

The ornamental design for a wall adapter, as shown and described.

DESCRIPTION

FIG. 1 is a front view of a wall adapter;
 FIG. 2 is a back view of the wall adapter;
 FIG. 3 is a left view of the wall adapter;
 FIG. 4 is a right view of the wall adapter;
 FIG. 5 is a top plan view of the wall adapter;
 FIG. 6 is a bottom view of the wall adapter; and,
 FIG. 7 is a perspective view of the wall adapter.
 The broken lines in the drawings depict portions of the wall adapter that form no part of the claimed design.
